UNITED STATES PATENT OFFICE

114,267

DESIGN FOR A PERPETUAL CALENDAR

Leonard P. Koprucki, Buffalo, N. Y.

Application February 23, 1939, Serial No. 83,170

Term of patent 14 years

To all whom it may concern:

Be it known that I, Leonard P. Koprucki a citizen of the United States of America, residing at Buffalo, county of Erie, State of New York, have invented a new, original, and ornamental Design for a Perpetual Calendar, of which the following is a specification, reference being had to the accompanying drawing, wherein:

Figure 1 is a front face view of a perpetual calendar, showing my new design.

Figure 2 is a top plan view.

I claim:

The ornamental design for a perpetual calendar, as shown.

LEONARD P. KOPRUCKI.
